UNITED STATES PATENT OFFICE.

JOSEPH FRANCIS DOLLES, OF CHESTER, ILLINOIS.

PIVOT-STRAIGHTENING TOOL.

1,182,658.

Specification of Letters Patent.

Patented May 9, 1916.

Application filed June 22, 1915. Serial No. 35,660.

To all whom it may concern:

Be it known that I, JOSEPH F. DOLLES, a citizen of the United States, and a resident of Chester, in the county of Randolph and 5 State of Illinois, have invented certain new and useful Improvements in Pivot-Straightening Tools, of which the following is a specification.

My invention relates to means for 10 straightening bent pivots on watch wheels, and one of the main objects thereof is to provide a tool or attachment for a watchmaker's lathe which will accomplish this result without any danger of breaking the 15 pivot or of injuring the wheel to which it is connected.

My invention is fully described in the 20 following specification, of which the accompanying drawings form a part, in which like characters refer to like parts in each of the views, and in which:—

Figure 1 is a central, longitudinal, section taken through a tool constructed in accordance with my invention, in inoperative 25 or relaxed position; Fig. 2 is a section taken on the line 2—2 of Fig. 1; Fig. 3 is a section taken on the line 3—3 of Fig. 1; and Fig. 4 is a view of a lathe with my tool in 30 position for use, a watch wheel being also shown.

In the drawings forming a part of this application I have shown one embodiment of my invention comprising a body member 5 and a nut 6 screw threaded thereon at 7, 35 said body member having an outwardly and forwardly flared head 8 against which the forward end 9 of the nut bears.

The head 8 is provided with a transversely and longitudinally arranged slot 10 40 extending from the forward end thereof to a point midway, approximately, of the length of the body member 5, a transverse bore 11 being provided to insure spring to the arms 12 and 13 formed by said slot, and 45 with a transverse bore 14 adjacent the forward end of said head, the slot and bores being in the same axial plane of the body member.

The body member is provided with a 50 tapered spindle 15 adapted for attachment to the tailstock spindle 16 of a watchmaker's lathe, whereby said body member may be held against rotation.

In practice, the wheel having the bent 55 pivot is firmly secured in the chuck 17 or headstock spindle of the lathe, the wheel

being shown at 18, and the chuck and wheel may be then rotated by belting or in any desired manner common to lathes.

The tailstock spindle is advanced until 60 the pivot of the watch wheel enters the slot 10 between the arms 12 and 13 at this time spread apart. The pivot may revolve in the slot 10 and, if greatly bent, may touch the inner surfaces of the arms in such revolution, which contact has a tendency to bend 65 the pivot back to normal position in a gradual manner as will be described. At first, this contact will be very slight if there is any at all but, as the nut 6 is screwed forwardly on the body member 5 the forward 70 end of the nut tends to force the arms 12 and 13 toward each other because of the tapered head 8, thus narrowing the slot 10 at its forward end and causing the arms to 75 advance gradually toward the axis of the tool and lathe at the same speed and in the same degree.

As the nut is advanced by the operator in a gradual manner, this contact between the 80 pivot and the inner surfaces of the arms becomes more and more pronounced, thereby moving the pivot more and more toward its normal position on the axis of the wheel; the advancing of the nut is continued until 85 the arms are in constant contact with the pivot, which condition can only obtain when the pivot is on the axis of the lathe and tool, the bore 14 serving as a peep hole for the operator to observe the operation. 90 While this operation is gradually performed it is also very quickly performed, the experience and skill of the operator guiding him as to the speed of advancement of the nut 6, and any equivalent for the nut 95 95 may be provided, as long as the broad idea of the slot to receive the pivot, and the means for gradually narrowing said slot, is maintained.

My invention is very simple though 100 highly efficient; it is readily connected with a lathe and as readily disconnected therefrom; there are no parts to be lost, and even an unskilled person may use the same and accomplish the best results; and the device 105 is comparatively inexpensive.

Having fully described my invention, what I claim as new, and desire to secure by Letters Patent, is:—

1. A tool for straightening the pivots of 110 watch wheels, comprising a body member provided with a longitudinally arranged

slot on the axis thereof to form spring arms between which said pivot is adapted to be arranged, means for moving said arms toward the axis of said tool, and means for attaching said tool to a relatively fixed portion of a lathe.

2. A tool for straightening the pivots of watch wheels, comprising a body member provided with a longitudinally arranged slot on the axis thereof to form spring arms between which said pivot is adapted to be arranged, means for moving said arms toward the axis of said tool, and a spindle on said body member adapted for connection with the tailstock spindle of a lathe.

3. A tool for straightening the pivots of

watch wheels, comprising a body member having a forwardly flared head provided with a longitudinal slot on the axis thereof to form spring arms, a nut threaded on said body member and bearing on said flared head for forcing said arms toward the axis of said tool, and a spindle for attachment with the tailstock spindle of a lathe.

In testimony whereof I have signed my name to this specification in the presence of two subscribing witnesses.

JOSEPH FRANCIS DOLLES.
